(57) **CLAIM**

The ornamental design for a touch screen with stand as shown and described.

DESCRIPTION

FIG. 1 is a front elevational view of a touch screen with stand showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, rear and right side perspective view thereof;

FIG. 9 is a bottom, rear and left side perspective view thereof;

FIG. 10 is an enlarged view of portion 10 in FIG. 7; and, FIG. 11 is an enlarged view of portion 11 in FIG. 7.

The evenly dashed broken lines in the drawings illustrate portions of the touch screen with stand which form no part of the claimed design.

The unevenly dashed broken lines illustrate the boundary of the enlarged views and form no part of the claimed design.

1 Claim, 11 Drawing Sheets
